WHEEL COVER

Leland W. Knight, Berkley, Mich., assignor to General Motors Corporation, Detroit, Mich., a corporation of Delaware

Filed Apr. 26, 1963, Ser. No. 74,643

Term of patent 7 years

(Cl. D14—30)

FIGURE 1 is a front elevational view of a wheel cover showing my new design;

FIGURE 2 is a sectional view taken generally along the plane indicated by line 2—2 of FIGURE 1;

FIGURE 3 is a side elevational view; and
FIGURE 4 is a perspective view.

I claim:

The ornamental design for a wheel cover, substantially as shown.
